UNITED STATES PATENT OFFICE.

GEORGE C. PRESCOTT, OF PEABODY, ASSIGNOR OF ONE-HALF TO JOSEPH H. POOR, OF SALEM, MASSACHUSETTS.

SAFE-LOCK.

SPECIFICATION forming part of Letters Patent No. 393,449, dated November 27, 1888.

Application filed December 13, 1887. Serial No. 257,750. (Model.)

To all whom it may concern:

Be it known that I, GEORGE C. PRESCOTT, of Peabody, county of Essex, and State of Massachusetts, have invented an Improvement in 5 Safe-Locks, of which the following description, in connection with the accompanying drawings, is a specification, like letters on the drawings representing like parts.

This invention relates to locks especially 10 adapted to be used on safes and vaults, it having for its object to provide a simple yet efficient lock.

My invention, therefore, consists, essentially, 15 in a safe or vault, of the door, and lugs or projections within the safe, combined with the gravity-lock composed of the frame-work of bars movable on said door and co-operating with the said lugs or projections to form a lock for the said safe, substantially as will be de- 20 scribed.

Other features of my invention will be pointed out in the claims at the end of this specification.

Figure 1 shows in elevation a safe or vault 25 provided with my improved lock, the door being wide open. Fig. 2 is a detail to be referred to; Fig. 3, a vertical section through the safe or vault with the door closed and locked; Fig. 4, a vertical section through the safe or 30 vault with the door closed but unlocked; Fig. 5, a section on either line xx or $x'x'$, Fig. 4; and Fig. 6, a detail, to be referred to.

The safe or vault A, of steel, brick, or other 35 suitable material, is provided with the usual door, A', preferably of steel. The door A' has secured to its inner side, by bolts a, blocks a', preferably V-shaped, as shown in Fig. 5, the said blocks constituting guides for bars a² a³. The bars a² a³ have secured to them, as shown, 40 by caps a⁴, one or more cross-bars, a⁵, which extend beyond the side bars, a² a³, they being of substantially the width of the safe or vault doorway. The side bars, a² a³, are herein shown as still further connected or joined together 45 by the cross-bar a⁶. The door A' has also secured to its inner side, beyond or outside the side bars, a² a³, by bolts b, additional bars b' b², preferably of considerable thickness, each bar being cut away (see Fig. 6) to form a pocket, 50 as at b³, when secured to the door, there being a pocket for each end of each cross-bar a⁵.

The cross-bars a⁵ are preferably made round, and the inner face of the bars a² a³, forming one side of the pocket b³, is preferably made convex or rounding, as shown in Figs. 5 and 55 6, to obtain the least possible contact of metal, thereby diminishing the friction between the bars b' b² and cross-bars a⁵. The ends of the cross-bars a⁵, beyond the side bars, a² a³, co-operate with lugs or projections b⁴, secured to or forming part of the sides of the safe or vault, there being preferably a lug for each end of each cross-bar a⁵.

The safe door is herein shown as provided with top bolts, b⁵, and bottom bolts, b⁶, movable 65 in guides b⁷ b⁸, secured to the said door. The top bolts, b⁵, are secured, as shown, to a bar, b⁹, and the bottom bolts, b⁶, to a bar, b¹⁰, the said bars being connected, respectively, by links c c' to opposite ends of a lever, c², pivoted at c³ 70 to the safe door. The lower bar, b¹⁰, as shown, has a stud, c⁴, to which is pivoted a device, c⁵, (herein shown as a lever,) adapted to be retained in position to be acted upon by the cross-bar a⁷ to shoot home the top and bottom 75 bolts, as will be described.

The side bar a³, as herein shown, is provided with a recess or notch, d, adapted to be engaged by a pin or stud, d', on a slide-bar, d², herein shown as acted on by a spring, d³, one end of 80 the said slide-bar engaging, as shown, a notch in a pivoted lever, d⁴, the said side bar a³ being retained in its elevated position by the slide-bar d² until the lever d⁴ is acted upon by a cam or stud, d⁵, on the door-casing, which occurs when the door is closed. 85

When the safe-door is open and the bolts and frame-work of bars in position to lock the door when closed, the said bolts and bars occupy the position shown in Fig. 1. 90

When the door is closed, the frame-work of bars is permitted to descend by gravity, as shown, by the stud d⁵ acting on the lever d⁴, thereby disengaging the pin d' from the notch d. The frame-work of bars descends from the 95 position shown in Fig. 1 to that shown in Fig. 3, the cross-bars a⁵ being behind and in line with the lugs or projections b⁴, thus securely locking the said door, the said gravity-lock or frame-work of bars being supported or sus- 100 tained in this position by a retaining device, herein shown as a slide-bar, e, (see Fig. 2,) hav-

- ing an arm, e' , extended in the path of movement of the cross bars a^5 , the middle cross-bar a^5 , as shown, resting upon the said arm when the door is locked.
- 5 When the gravity-lock or frame-work of bars falls from the position shown in Fig. 1 to that shown in Fig. 3, the cross-bar a^5 acts upon the device e^6 , disengaging it from its catch e^6 and shoots the top and bottom bolts home through 10 the link e^6 and lever e^6 . The door A' remains locked as long as the slide-bar is retained in the position shown in Fig. 3 and by full lines, Fig. 2, by a pin, e^6 , on a lever, e^6 , having an arm, e^6 , engaged by a cam or disk, 15 e^6 , pivoted, as shown, to one side of the door-casing, the said cam or disk being connected to and operated by a time-lock of usual construction and not herein shown. The cam or disk e^6 has a flat portion or notch, e^6 , in its 20 periphery, into which the arm e^6 drops when the proper time has arrived to open the safe, the said cam or disk being rotated in the direction of arrow 20 through the time-lock, the lever e^6 descending into the dotted-line position shown in Fig. 2, thus disengaging the pin e^6 from the bar e^6 and permitting the said bar and gravity-lock to drop into the position shown in Fig. 4, the cross bars a^5 being below the lugs or projections b^4 .
- 25 The top and bottom bolts are withdrawn from their sockets when the gravity-lock descends into the position shown in Fig. 4, as herein shown, by the uppermost cross-bar a^5 acting on a stud, e^{10} , secured to the bar b^4 , thus 30 allowing the door to be opened. After the door is opened, the gravity-lock or frame-work of bars may then be raised to place it in operative position by turning the pinion f engaging teeth f' , herein shown on the side bar a^6 , the pinion being provided, as shown, with 35 a square arbor to be engaged by a suitable handle. (Not shown.) The device e^6 will be turned from the position shown in Fig. 4 to that shown in Fig. 1 by hand.
- 40 45 It will be noticed that the time lock is placed within the safe and away from the door, thus diminishing the danger of stopping the said time-lock by concussion produced by blows or from other source.
- 50 I claim—
1. In a safe or vault, the door, lugs or projection within the safe, a gravity-lock composed of a frame-work of bars movable on the said doors, and a retaining device to normally 55 hold the gravity-lock in elevated position above the lugs, combined with a cam or pro-

jection within the safe or vault to act upon or release the said retaining device when the door is closed, substantially as and for the purpose specified.

60

2. In a safe or vault, the door and a gravity-lock composed of side and cross bars movable on said door and lugs or projection b^4 within safe to co-operate with the said frame-work of bars, combined with a retaining device, e , to 65 retain the said cross bars behind and in line with the said lugs or projections, substantially as described.

65

3. In a safe or vault, the door and a gravity-lock composed of side and cross bars movable 70 on said door and lugs or projections b^4 within the safe to co-operate with the said frame-work of bars, combined with a retaining device, e , to retain the said cross bars behind and in line with the said lugs or projections, and with a 75 device operatively connected to the time-lock to release the retaining device e and permit the gravity-lock to descend in a position below the lugs or projection to unlock the door, substantially as described.

80

4. In a safe, the door and bars $b^4 b^4$, secured thereto and provided with pockets, as b^3 , combined with a gravity-lock composed of side bars, $a^2 a^3$, and cross-bars a^5 , the said cross-bars being extended through said pockets, and with 85 lugs or projections b^4 to co-operate with said cross-bars to lock the door, substantially as described.

85

5. In a safe or vault, the combination, with a gravity-lock composed of side bars, $a^2 a^3$, and 90 cross-bars a^5 , of lugs or projections b^4 within the safe, and with which the gravity-lock co-operates to lock the said door, and top and bottom bolts adapted to be operated, as described, by the said gravity-lock, as and for 95 the purpose specified.

90

6. In a safe or vault, the combination, with a gravity-lock composed of side bars, $a^2 a^3$, and cross-bar a^5 , of top and bottom bolts and links e^6 and lever e^6 to connect said bolts, and device e^6 , adapted to be normally retained in position to be acted upon by the gravity-lock to lock the said top and bottom bolts, substantially as specified.

100

In testimony whereof I have signed my name 105 to this specification in the presence of two subscribing witnesses.

GEORGE C. PRESCOTT.
